(57) CLAIM

The ornamental design for the pair of shoes, as shown and described.

DESCRIPTION

FIG. 1 is a right-side perspective view of the right shoe of the pair of shoes showing my new design;

FIG. 2 is a left-side view of the design of FIG. 1;

FIG. 3 is a right-side view of the design of FIG. 1;

FIG. 4 is a front view of the design of FIG. 1;

FIG. 5 is a back view of the design of FIG. 1;

FIG. 6 is a top view of the design of FIG. 1; and,

FIG. 7 is a bottom view of the design of FIG. 1.

FIGS. 1 through 7 depict the right shoe of the pair of shoes, the left shoe being a mirror image thereof.
